VEHICLE FLOOR SKID RAIL AND SECURING MEANS

Nelson E. Cole, Reading, Pa., assignor to Dana Corporation, Toledo, Ohio, a corporation of Virginia
Application March 20, 1952, Serial No. 277,655
2 Claims. (Cl. 189—34)

This invention relates to vehicle floors and is more particularly directed to an improved metallic skid rail and joint member for truck, trailer or other commercial vehicle floors fabricated primarily of wood or other non-metallic material.

An object of the present invention is to provide a combined skid rail and joint member suitable for attachment to a floor board prior to the installation of the floor boards over the cross sills of the vehicle.

Another object of the invention is to provide means for sealing or closing the joints between the floor boards while permitting normal expansion and contraction of the wood or other floor board material due to moisture or other variables.

Another object of the invention is to provide a floor board with an improved skid rail and joint member which combination does not require the use of bolts, screws or the like or the drilling of holes to secure the floor to the cross sills of the vehicle.

Still another object of this invention is to provide a positive metallic reinforcement for floors which increases the bearing and bending resistance capacity of the floor boards between the cross sills as well as protecting the edges of the floor boards from crushing or splintering.

Still a further object of the invention is to provide an improved method of preparing floor boards for installation in such a manner that a minimum of time is required to build a complete floor.

Further objects and advantages will become apparent from a study of the following description when taken in connection with the accompanying drawings, in which:

Figure 1 is a fragmentary perspective view of a portion of a vehicle floor incorporating the present invention.

Figure 2 is a sectional detail view illustrating the attachment of the skid rail to a vehicle cross sill;

Figure 3 is an end view of a floor board with a skid rail about to be applied.

Figure 4 is a perspective view of a portion of the skid rail shown in Figure 1; and

Figure 5 is a view similar to Figure 3 showing a modified form of the invention.

Referring to the drawings Figure 1 illustrates a portion of a vehicle floor which incorporates the present invention, the floor 10 being laid directly on the usual cross sills 11 of conventional channel form. A plurality of parallel boards 12 of wood or the like are secured to the sills after having previously been prepared for such installation. Each board is provided with an undercut portion 14 in one face 16 adjacent an edge 18 thereof. It will be noted that this cut is considerably more shallow than the usual ship-lap.

To edge 18 of the floor board 12 is applied a metallic member 20 generally Z shaped in cross section having a web portion 22 and leg or flange portions 24 and 26 extending in opposite directions from the web 22 at substantially right angles thereto. The web of the Z member is preferably pierced at spaced points 27 to receive fasteners such as the nails 28 adapted to be driven into the board 12. It will be noted that the nails 28 are preferably short and heavy so that they may be driven into hard wood boards such as oak or the like. When the member 20 is assembled with the board 12 the leg 26 provides a flange which overlies the next adjacent board, such board being provided with an undercut portion 30

2

to receive the leg 26. The flange provided by leg 26 is of sufficient width to cover the marginal edge of the adjacent board sufficiently to compensate for shrinkage, it being unnecessary and in fact undesirable to butt the edges of adjacent boards together tightly. The free edge of leg 26 may be turned downwardly slightly to provide a seal at its line of contact and thus between two adjacent boards.

Should it be desirable to use floor boards of the softer woods, the skid rail shown in Figure 5 may be used. In this type of rail it will be noted that instead of providing the web with perforations to receive separate fasteners, the web may be formed with integral fastening means such as the points 34 cut and bent out of the plane of the web so that they are at right angles to the web. It will be clear that this arrangement eliminates the need for separate fasteners, it being necessary only to lay the strip on the edge of a board and drive the points 34 into the wood.

After the complete floor is laid on the sills 11 it is desirable to secure it in place which now becomes a very easy and fast operation. It will be noted that as each lower flange of the skid rail engages the top flanges of the cross sills, as shown in Figure 2, it is only necessary to weld flange 24 to the flange 38 at each juncture. By so doing it will be clear that not only is the floor secured firmly to the sills but also the entire structure greatly strengthened by increasing the bearing capacity of the floor and also increasing its resistance to bending.

What I claim is:

1. In a vehicle body having a plurality of cross sills, a flooring for said body comprising a plurality of laterally spaced boards, each of said boards being provided with a skid rail having a web portion secured to one edge thereof, said skid rail having a horizontal portion spanning the space between adjacent floor boards, and a second horizontal portion underlying only the board to which it is secured and said underlying portion engaging the cross sills, and welds between each of said sills and said underlying portions of said skid rails, said welds being the only means to secure said flooring to said cross sills, the space between said boards being such that free expansion and contraction is permitted while still confined by the first horizontal portion of said skid rail.

2. In a vehicle body having a plurality of cross sills, flooring for said body comprising a plurality of preassembled floor boards and Z-shaped metallic joint members, each of said joint members having a web portion secured to an edge of its respective board, said flooring being arranged on said sills so that one horizontal flange of the joint member overlies the next adjacent board and the other horizontal flange of the joint member underlies only the board to which it is secured and engages the cross sills, the underlying portions being subsequently secured to said sills by a weld at each of said sills, said boards being secured in position on said cross sills solely by said joint members.
